UNITED STATES PATENT OFFICE

GUY A. DUNN, OF SAN FRANCISCO, CALIFORNIA, ASSIGNOR TO EBY MANUFACTURING COMPANY, OF SAN FRANCISCO, CALIFORNIA, A CORPORATION OF CALIFORNIA

DISCHARGE MECHANISM FOR TYING MACHINES

Application filed July 30, 1928. Serial No. 296,334.

This invention relates to a package discharge for tying machines, and the object of the invention is to take the packages away from the machine as soon as the tie 5 around the package has been completed.

This package discharge consists of a pair of belts and a plurality of notched disks which disks and one end of the pair of belts rises to lift the package off of the support 10 upon which it is placed during the time the tie is being made around it, and carry it away from the tying machine to discharge it upon a table or other endless belt for taking the package to a place of storage.

It will be understood by those skilled in the art that the machine upon which this discharge is applied carries packages so rapidly that it is very difficult for the attendant to push the packages through the 15 machine with sufficient rapidity to get the tied package out of the way of the package to be tied, unless the workman can devote his entire attention to the placing of the new package to be tied, and then he has all he 20 can do to keep the package placed in the proper position for tying without attending to the discharge of the package that has been tied.

Other objects of the invention will be apparent as the description proceeds.

An embodiment of the invention is shown in the accompanying drawings in which the same reference numeral is applied to the same portion throughout the several figures 35 of the drawings, and of which there may be modifications.

Figure 1 is a vertical elevation of the discharge side of a tying machine of this type showing the discharge belt applied thereto,

Figure 2 is a view partly in section at the discharge belt,

Figure 3 is a sectional view of the pulleys used to carry the discharge belt,

Figure 4 is a plan view of the discharge table at the discharge belt, and

Figure 5 is a view partly in section of a detail showing the driving gears for driving the discharge belt.

The tying machine is of a well known type 50 in which there is a base 1 containing most

of the operating cams and shafts, extending upwardly from this base is a heavy fixed ring 2 which carries a plurality of wheels 3, 4, 5 and 6 for the support of the rotary shuttle ring 7.

Just in front of the machine there is a table 8 which has a fixed side fence 9 to align the packages against it when they are to be tied; a jogger 10 causing the packages to be pushed against the fence and holding them in that 55 position until the tie has been completed. The machine is driven from the motor M which sits upon the bracket 12 at one side of the main ring 2. The motor has two pulleys 13 and 14 around which pulleys pass the belts 60 15 and 16 respectively. The belt 16 drives the main pulley 17 which is on a shaft 18 carrying a worm gear which drives the worm wheel 19, the latter on the shaft 20.

The shaft 20 has the key 21 in engagement 65 with the cam gear 22, said cam gear having a groove on one side thereof to receive the roller 23 which is secured to an arm 24 for the operation of the link 25 which raises and lowers the package discharge belt. The shaft 20 70 75 also carries a pulley 26 which is pivotally connected by means of the pin 27 to a pitman 28, said pitman having a series of teeth thereon which engage the teeth of the spur gear 30.

The spur gear 30 is secured to a shaft 31 80 which is journalled in boxes 32, 33 and has a bevel gear 34 thereon to drive the bevel gear 35 which operates that portion of the tying machine which is engaged in making the tie and rotating the ring 7 but which forms 85 no part of the present invention.

Extending from the rearward side of the ring 2 are three table members 36, 37, 38.

The shaft 41 is journalled in two bearings 90 47, 48 which are bolted onto the side of the frame of the machine at the back of the ring 2 by means of two brackets 49, 50. The bearing 47 has an arm 51 mounted thereon which carries a stud shaft 52 for the support of the belt tightener 53. The hub of the arm 51 is split and has two lugs 54, 55 which enable the bolt 56 to tighten the hub on the extension of the bearing 47 to hold the belt tightening pulley 53 in a given adjustment. The belt 57 95 passes around the pulley 53 around the pulley 100

42' and then around a pulley 59 just back of the table, the latter pulley being loosely mounted on a shaft 60. Upon the shaft 60 is also loosely mounted a rear pulley for the belt 61.

5 The belt 61 passes around the tightening pulley 62, and around the front pulley 63, as well as over the pulley 64. The belt 57 also 10 passing over a similar pulley 64' to allow the link 25 to raise and lower the belt without increasing their tension materially by reason of the fact that both of them pass over the two pulleys 64, 64' on the shaft 41.

15 The belt tightener pulley 62 is carried by a stud shaft 65, the same as the stud shaft 52 and the arm 66 supports it. Both the arms 51 and 66 are supported on extensions of the bearings 47, 48 and are locked in their positions by bolts 56 passing through the arm lugs 20 54 and 55, one set for each arm.

25 In order to provide for driving the belts 57 and 61 there is a housing 70 at the end of the bearing 48 to cover the drive gears and form bearings therefor. This housing 70 has bearings for the shaft 41, 76 and 78 which are also journalled in the cover plate 71.

30 The shaft 41 is driven by the gear 74, gear 75, gear 77 on the shaft 78, bevel gear 79 on the shaft 78 and bevel gear 80 on the shaft 81, the latter shaft carrying the drive pulley 82.

35 In operation the cam 26 which drives the lever 24 and raises and lowers the belt with its associated serrated disk pulleys operates to raise the belt and serrated disks at the end of the cycle of the tying mechanism. In other words as soon as the tie is completed and any other thing that has to be done with respect to the tie is effected the cam comes into movement 40 to engage the serrated disks with the bottom of the box, and thereby carry the bundle away from the machine, the belt aiding the serrated disks. The disks operate all the time but do not move the box until the tie is complete.

45 It will also be seen that the entire weight of the box or bundle is carried by the table during the period of tying, that there is no danger of the box moving at the wrong time, 50 but the belts are always lifted higher than the table so they carry all of the weight of the box and quickly move it away from the machine.

55 Having thus described my invention, what I desire to secure by Letters Patent of the United States is as follows, but modifications may be made in carrying out the invention as shown in the drawings and in the above 60 particularly described form thereof, within the purview of the annexed claims.

65 1. A discharge mechanism for tying machines comprising the combination of a carrier; and means to lift the carrier into contact with the bundle at the end of each tie

whereby the bundle will be discharged from the machine.

2. A discharge mechanism for a bundle tying machine including an oscillatory carrier therefore and means to oscillate said carrier into engagement with the bundle to remove the bundle from the machine every time a tie is made by said machine. 70

3. A discharge mechanism for a bundle tying machine including an endless oscillatory carrier and means to oscillate said carrier into engagement with the bundle to remove the bundle from the machine each time a tie is made around said bundle. 75

4. A discharge mechanism for bundling machines comprising the combination of an endless carrier; a series of serrated disks operating in connection with said carrier; and means to lift the disks and carrier into contact with the bundle each time a tie is made around the same. 80

5. A discharge mechanism for bundling machines comprising the combination of an endless carrier; pulleys around which the carrier passes, means to raise and lower one end of the carrier so that upon the completion of each tie the bundle will be carried from the machine. 90

6. A discharge mechanism for bundling machines, comprising the combination of a pair of endless carriers; pulleys around which said carriers pass means for raising and lowering one set of said pulleys to bring the carrier into contact with the underside of the bundle whereby upon the completion of tying, the bundle will be lifted to be carried away from the machine. 95

100 7. A discharge mechanism for bundling machines comprising the combination of a pair of endless carriers; a series of pulleys around which the endless carrier passes means for movably mounting one of said pulleys for each carrier whereby one loop of the endless carrier is raised and lowered; means to effect said raising and lowering; and a series of serrated disks to aid in steering the bundle as it is discharged from the machine following each tie. 110

115 8. A discharge mechanism for a bundle tying machine including a movable carrier, a driving means for said carrier, a means for moving said movable carrier into contact with the bundle to remove the bundle from the machine each time a tie is made around said bundle. 120

125 9. A discharge mechanism for bundle tying machines including a movable carrier, a means for driving said carrier, a series of serrated discs operatively associated with said carrier, and means for moving said carrier and discs into contact with the bundle to remove the bundle from the machine each time a tie is made around said bundle.

130 10. An automatic discharge mechanism

- for bundling machines including an endless carrier, means for driving said carrier, means operable for raising one end of said carrier upon the completion of the tie to discharge
5 the bundle and operable for lowering the raised end of said carrier during the tying operation so that the carrier will not disturb the bundle during the tying operation.
11. A discharge mechanism for bundle
10 tying machines including a pair of endless carriers, a plurality of pulleys for each carrier, means for driving one of said pulleys for each carrier and means operatively associated with the tying machine driving
15 mechanism operable to move another of said pulleys for each carrier to move said carriers into engagement with the bundle upon completion of the tie to discharge the bundle from the machine and operable to move said
20 movable pulleys out of engagement with said bundle during the bundle tying operation.
12. A discharge mechanism for bundle tying machines including a pair of endless carriers, means for independently tightening each of said carriers, means for driving each of said carriers, and means operable from the tying machine mechanism for raising and lowering said endless carriers.
13. A discharge mechanism for bundle
25 tying machines including a carrier, means for tightening said carrier, means for driving said carrier, and means for lifting said carrier into contact with the bundle at the end of each tie whereby the bundle will be discharged from the machine.

In testimony whereof I have hereunto set
my hand this 20th day of July, A. D. 1928.
GUY A. DUNN.
